US0D1056348S

(12) **United States Design Patent** (10) **Patent No.:** **US D1,056,348 S**
(45) **Date of Patent:** **** Dec. 31, 2024**

(54) **SET OF ARTIFICIAL LASH EXTENSIONS**

(71) Applicant: **Lashify, Inc.**, North Hollywood, CA (US)

(72) Inventor: **Sahara Lotti**, North Hollywood, CA (US)

(73) Assignee: **Lashify, Inc.**, North Hollywood, CA (US)

(**) Term: **15 Years**

(21) Appl. No.: **29/936,393**

(22) Filed: **Apr. 8, 2024**

Related U.S. Application Data

(62) Division of application No. 29/909,774, filed on Aug. 10, 2023, now Pat. No. Des. 1,026,333.

(57) **CLAIM**

The ornamental design for a set of artificial lash extensions as shown and described.

DESCRIPTION

FIG. 1 is a top right perspective view of a set of artificial lash extensions in accordance with the claimed design showing the order for the right eye.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a top left perspective view of a set of artificial lash extensions showing the order for the left eye.

FIG. 9 is a front view thereof.

FIG. 10 is a rear view thereof.

FIG. 11 is a right side view thereof.

FIG. 12 is a left side view thereof.

FIG. 13 is a top view thereof; and,

FIG. 14 is a bottom view thereof.

The broken lines consisting of evenly spaced lines in the figures show portions of the artificial lash extensions that form no part of the claimed design. The broken lines consisting of evenly spaced lines illustrating environmental structure in the figures form no part of the claimed design.

1 Claim, 12 Drawing Sheets
